Primary Examiner—M. H. Tung*(74) Attorney, Agent, or Firm*—Burns, Doane, Swecker & Mathis, LLP**(57) CLAIM**

The ornamental design for a user interface for a computer display, as shown and described.

DESCRIPTION

FIG. 1 is a front view of a user interface for a computer display showing our new design;

FIG. 2 is a front view of a second embodiment thereof;

FIG. 3 is a front view of a third embodiment thereof; and, FIG. 4 is a front view of a fourth embodiment thereof.

The broken line drawings of a computer display, windows, words, letters, and other features in all views are for illustrative purposes only and form no part of the claimed design.
